DESIGN FOR A LAMP

Wyllis F. Pulver, Rensselaer, N. Y.

Application March 27, 1935, Serial No. 56,083

Term of patent 7 years

To all whom it may concern:

Be it known that I, Wyllis F. Pulver, a citizen of the United States, residing at Rensselaer, county of Rensselaer, and State of New York, have invented a new, original, and ornamental Design for Lamp of which the following is a specification, reference being had to the accompanying drawing, forming a part thereof, in which—

Fig. 1 is a front elevational view of the lamp showing my new design;

Fig. 2 is a side elevation of the lamp with the shade removed; and

Fig. 3 is a section of Fig. 2 in the plane 3—3 to show the top view of the base of the lamp.

The figures in the drawing are ruled to show the colors red and black.

I claim:

The ornamental design for a lamp as shown and described.

WYLLIS F. PULVER.
